[57] CLAIM

The ornamental design for an electric hot plate for heating deodorant tablets for insertion in the electric lighter outlet of a motorvehicle or the like, as shown and described.

DESCRIPTION

FIG. 1 is a top front perspective view of an electric hot plate for heating deodorant tablets for insertion in the electric lighter outlet of a motorvehicle or the like, showing my new design;

FIG. 2 is a side elevation view thereof, the opposite side

being a mirror image of that shown;

FIG. 3 is a top plan view thereof;

FIG. 4 is a bottom plan view thereof;

FIG. 5 is a front elevation view thereof; and

FIG. 6 is a rear elevation view thereof.

FIG. 1

FIG.2
